UNITED STATES PATENT OFFICE.

SAMUEL G. SHAPIRO, OF NEW YORK, N. Y.

DEVICE FOR USE IN ATTACHING HEELS TO SHOES.

1,401,819.

Specification of Letters Patent. Patented Dec. 27, 1921.

Application filed December 22, 1919, Serial No. 346,641. Renewed May 14, 1921. Serial No. 469,481.

To all whom it may concern:

Be it known that I, SAMUEL G. SHAPIRO, a citizen of the United States, residing at New York, in the county of New York and 5 State of New York, have invented certain new and useful Improvements in Devices for Use in Attaching Heels to Shoes, of which the following is a full, clear, and exact description, such as will enable others 10 skilled in the art to which it appertains to make and use the same.

This invention relates to devices for use in attaching heels to shoes, and more particularly to devices employed in attaching 15 high heels, of the French or Cuban style, to women's shoes.

It is an object of the invention to provide an improved and simplified unitary device wherewith the attachment of heels of the 20 character mentioned is facilitated and expedited.

Another object is to provide a compact and durable apparatus for the purpose described and which is capable of adjustment 25 for use with different styles of heels.

Other objects and advantages will be in part obvious and in part noted hereinafter in connection with the following description of the accompanying drawings which illustrate a preferred embodiment of the invention, and in which—

Figure 1 is a fragmentary perspective of the device and

Fig. 2 is a top plan view thereof.

35 Referring more particularly to the drawings, the device is shown as comprising a flat supporting base 1 having rigidly affixed thereto an upright backing block 2 at one end and a clamping holder 3 at the other 40 end. The base 1 is preferably of triangular shape with the block 2 located adjacent one apex and the clamp 3 extending between the other two apices.

Block 2 is preferably of metal or other 45 durable material and is shaped to provide a flat top 4 and a narrowing body 5 of a size to fit within the heel portion of an inverted shoe ready to have a heel attached thereto. As above indicated, the device is particularly 50 designed for use in applying high heels, and especially metal heels of the character shown in my copending applications, Serial Nos. 304,129, 306,456, 321,084, 325,249, and 343,278.

55 In order to serve as a rigid backing for the shoe during attachment of the heel, and

to permit proper and expeditious penetration of the nails or similar elements through the shoe bottom, the block 1 is provided around its top edge with a plurality of recesses 6 located to receive the nails as driven without bending or clinching. After this operation, the shoe is removed from block 1 and transferred to the clamp 3, which latter includes a rigid upright curved plate 60 7 having an open side 9 and shaped, in general, to fit about the rear and sides of the heel previously attached. The second clamping element of device 3 is an adjustable plate 8 supported on base 1 and mounted to fit 65 and slide on parallel guides 14 preferably integral with the base. A stud 10 is secured to plate 7 and has a threaded end 11 projecting through plate 8 with a manipulatable nut 12 thereon, whereby plate 8 may be 70 drawn toward the open side of plate 7 to grip securely therebetween the previously 75 attached shoe heel.

It will be noted that the configuration of plates 7 and 8 and the relative adjustment 80 thereof allows the reception therebetween of high heels either of the French or Cuban style. Furthermore a softer material, such as felt or the like, may be used to line the clamping member to prevent marring the 85 heel surfaces. As the movable plate 8 is also held against twisting movement by the guides 14, it will be apparent that the shoe heels may be expeditiously positioned and firmly held in the clamp. While thus 90 gripped the ends of the nails or the like driven in on the block 2 may be bent and clinched with the usual tools.

For convenience base 1 also is provided with grooves 13 along the sides to hold the 95 shoemaker's tools.

The apparatus as thus described constitutes a unitary, compact, portable and especially efficient adjunct for the purposes set forth. The device is relatively light in 100 weight, strong and durable, and by its use the attachment of heels to shoes is rendered easy and quick. The clamp 3 is of especial advantage, also, in that it acts to receive and grip heels of varying sizes and shapes. 105

Having thus described my invention, what I claim as new and desire to secure by Letters-Patent, is:

1. In a device of the character described, in combination, a supporting base, an up-standing metal block thereon having an end to fit in an inverted shoe and having spaced 110

recesses around its upper edge to receive nails penetrating said shoe, and an upstanding adjustable clamp on said base to receive a shoe heel.

- 5 2. In apparatus of the character described, in combination, a supporting base having integral guides thereon, a rigid curved plate upstanding therefrom and laterally open in one direction, a complementary upstanding member opposite the open side of said plate, and a stud secured to said plate having a threaded end projecting through the complementary member with a manipulatable

nut thereon whereby said complementary member may be drawn toward the open side 15 of said rigid curved plate on said guides, said rigid plate and said complementary member being shaped so that the relative adjustment thereof allows the reception of a shoe heel therebetween. 20

In witness whereof, I affix my signature, in the presence of two witnesses.

SAMUEL G. SHAPIRO.

Witnesses:

MYRTLE B. PITZER,
B. J. LONGSTREET.
